TRICYCLE

John W. Ryan, Bel Air, Calif., assignor to Mattel, Inc.,
a corporation of California

Filed Apr. 8, 1964, Ser. No. 79,415

Term of patent 14 years

(Cl. D34—15)

FIGURE 1 is a perspective view of a tricycle showing my new design;

FIGURE 2 is a side view of the tricycle shown in FIGURE 1;

FIGURE 3 is a top view of the tricycle shown in FIGURE 1; and

FIGURE 4 is a rear view of the tricycle shown in FIGURE 1.

The dominant features of the design reside in the portions shown in full lines.

I claim:

The ornamental design for tricycle, substantially as shown and described.
